UNITED STATES PATENT OFFICE.

CHARLES W. HAWTHORNE, OF SHREWSBURY, MASSACHUSETTS, ASSIGNOR TO WICK-WIRE SPENCER STEEL COMPANY, OF NEW YORK, N. Y., A CORPORATION OF DELAWARE.

MESH-ALIGNING DEVICE FOR WIRE-NETTING MACHINES.

Application filed July 27, 1925. Serial No. 46,276.

This invention relates to machines for making hexagonal mesh wire netting, such as the usual poultry netting. In forming such wire netting, a series of filling wires 5 and a series of reel wires are first twisted together in successive pairs and the reel wires are then shifted transversely to match them with the next adjacent filling wires. At the same time, the take-up roll and the 10 netting already formed is shifted axially, approximately one-half of the distance between adjacent twists in the fabric.

In wire netting machines as previously operated, the woven fabric and the wire 15 from which the fabric is formed have been unsupported between the twisting gears and the take-up roll, and the position assumed by the wires has been determined largely by the relative tension of the reel and filling 20 wires. Substantial differences in tension between the two sets of wires resulted in the formation of unsymmetrical and irregular meshes in the fabric.

It is the object of my present invention 25 to provide means for accurately positioning the fabric and the wires transversely closely adjacent the twisting point, so that the successive meshes may be symmetrical in form and that they may also be symmetrically 30 arranged with relation to the preceding meshes. For the attainment of this object I provide positioning members positively 35 engaging the last formed twists in the fabric and positively moving the same laterally to a position exactly mid-way between the 40 points at which the next twists are to be formed.

My invention further relates to arrangements and combinations of parts which will 45 be hereinafter described and more particularly pointed out in the appended claims.

A preferred form of the invention is shown in the drawings in which

Fig. 1 is a sectional side elevation of parts of a wire netting machine embodying my 50 improvements;

Fig. 2 is a front elevation thereof, taken along the line 2—2 in Fig. 1;

Fig. 3 is a partial plan view, looking in 55 the direction of the arrow 3 in Fig. 1;

Fig. 4 is a view showing one step in the operation of the machine wherein the mesh aligning bars engage a twist;

Fig. 5 shows a subsequent step in the operation of the machine wherein the twist 55 has been drawn above the mesh aligning bars, the several elements being in process of shifting from the position shown in Fig. 4;

Fig. 6 is a subsequent step wherein certain of the mesh aligning bars have engaged another twist;

Fig. 7 is a view showing a step similar to Fig. 5, but wherein the several elements are in the course of shifting back to the position shown in Fig. 4; and

Fig. 8 is a detail view of one of the aligning arms, to be described.

Referring to the drawings, I have shown parts of a wire netting machine including 70 a take-up roll 10 having staples or projections 11 thereon adapted to engage the fabric and to draw the fabric upward from the twisting devices. A stationary plate 12 is mounted below the take-up roll 10 and is 75 provided with a longitudinally extended recess 13 in which a driving rack 14 is slidably mounted. The rack 14 engages a series of half gears 16, each mounted upon a rotatable support 17 and having a half bearing 80 in the plate 12. A second half gear 18 is associated with each half gear 16 and each pair of half gears 16 and 18 collectively forms one of the twisting gears of the machine.

The gears 18 are provided with half bearings in a sliding plate 20 mounted for movement longitudinally of the machine and held in position by a guide plate 21 and adjusting screw 22. The sliding plate 20 rests 85 upon a fixed frame member 23 forming a portion of the frame of the machine. A holding rack 24 is mounted to slide in the plate 20 and is effective to hold all of the half gears 18 in the same angular relation 90 but is not used for rotating the gears.

A shell 25 fits over the lower end of each rotatable gear support 17 and positions the upper end of a filling bar 26 upon which the filling wire W is wound. The wire W 100 passes upward through an opening 28 within the support 17 and the wire is delivered from the support at the upper end as clearly shown in Fig. 1.

The wires R are delivered from reels or 105 spools (not shown) and each wire R passes

upward through an opening 29 in a projection 30 extending downward from one of the half gears 18. The wires R are delivered from the upper ends of the supporting structures for the half gears 18, adjacent the point of delivery of the wires W.

If the twisting gears formed of the half gears 16 and 18 are now rotated by means of the driving rack 14, the wires W and R will be twisted around each other, forming a twist in the fabric, as clearly indicated in Figs. 4 to 7, successive twists being formed by rotation in opposite directions. After one twist has been formed, the sliding plate 20 with its half gears 18 is moved longitudinally to align each gear 18 with the next adjacent half gear 16, so that the pairing of the filling and reel wires is changed after each line of twists has been formed in the fabric.

The parts thus far described are of the usual type and in themselves form no part of my present invention which relates particularly to means for guiding the wires between their points of delivery from the twisting gears and their point of attachment to the take-up roll 10. For this purpose, I provide two series of positioning devices. For supporting one series of positioning devices, I provide an angle iron 35 fixed to the stationary plate 12 and having a series of projections 36 secured thereto and each providing a bearing for a pivoted arm 37.

Each arm 37 is loosely mounted in its projection 36 so that it has limited lateral movement as indicated in Fig. 8. Each of the arms 37 is free to move upward, as the take-up roll is rotated, to clear the cross wires of the fabric as they engage the arms 37.

I provide a second angle plate 40 on the sliding plate 20 for the support of the second series of positioning devices. This angle plate 40 is not bolted directly to the plate 20 but the bolts 41 extend through slots 42 (Fig. 3) permitting a definite amount of lost motion, so that the travel of the plate 40 is substantially less than that of the sliding plate 20.

A series of projections 44 are secured to the plate 40 and these projections are slotted to provide bearings for positioning members 45 pivoted in said projections at 46. A spring 47 holds each member 45 normally in the position shown in Fig. 1 but permits said members to yield upwardly, when engaged by a cross wire of the fabric. At their outer ends the members 45 are increased in width as indicated at 48.

Having described the details of construction of my improved mesh-aligning devices, I will now describe the operation thereof, referring particularly to Figs. 4 to 7. In Fig. 4 the parts are shown with the half gears 18 shifted to the left, as viewed in the draw-

ings, and with the twisting gears just commencing the formation of a series of twists in the fabric. The preceding twist A has been fed upwardly and laterally and each twist is engaged by an arm 37 on one side thereof and by a positioning member 45 on the opposite side thereof. These arms and members are so positioned that each twist A is exactly half way between the axes of two adjacent twisting gears.

The twisting gears are then rotated and the fabric is fed upward as indicated in Fig. 5, forming twists B uniformly positioned with relation to the preceding twists A. The take up roll is then shifted to the right (by mechanism not shown) a distance equal to one-half of the space between two adjacent twisting gears. By such movement each arm 37 is engaged on the opposite side thereof and is swung side-ways from the full to the dotted line position shown in Fig. 8, so that while each twist B engages its arm 37 upon the opposite side thereof, it is still exactly centered between two adjacent twisting gears.

The members 45 at the same time have received a transverse motion with the sliding plate 20 but by reason of the lost motion connection therewith, this transverse movement is just sufficient to cause the right hand edge of each member 45 to press a twist B against the left hand side of the arm 37. The twists are each thus definitely positioned exactly half way between the axes of two adjacent twisting gears, which are then rotated to form the next series of twists C as indicated in Fig. 7. The parts thereafter return to the position indicated in Fig. 4 and the sequence of operations is repeated.

It will be noted by a comparison of Figs. 4 to 7 with Figs. 2 and 3, that the element 45 is pictured in Figs. 2 and 3 as nearly completing the shift to the left. When completed elements 45 and 37 will be in the position indicated in Fig. 4; element 45 engages the element 37 to the left for twist A and engages a different element 37 on its right for twist B, this element 45 being mounted as stated heretofore to shift with plate 20.

It will thus be evident that I have definitely positioned and held each twist of the fabric during the formation of the next succeeding series of twists, thus producing substantially uniform and substantially symmetrical meshes in the fabric and thus avoiding the injurious results caused by irregular tension in the wires W and R.

Having thus described my invention and the advantages thereof, I do not wish to be limited to the details herein disclosed otherwise than as set forth in the claims, but what I claim is:

1. In a wire netting machine, means to twist the wires, means to shift the wires lat-

erally, and means directly engaging the last formed portion of the fabric to limit the lateral movement thereof.

2. In a wire netting machine, means to twist the wires, means to shift the wires laterally, and means directly engaging the last formed portion of the fabric to limit the lateral movement thereof in both directions.

3. In a wire netting machine, means to twist the wires, means to shift the wires laterally, a positioning device mounted upon a fixed support and engaging one side of each last-formed twist, and a second positioning device mounted upon a transversely movable support and engaging the opposite side of each such twist.

4. In a wire netting machine, means to twist the wires, means to shift the wires laterally, a positioning device mounted upon a fixed support and engaging one side of each last-formed twist, and a second positioning device mounted upon a transversely movable support and engaging the opposite side of each such twist, said support being mounted for transverse movement with said twisting means, and having a lost motion connection therewith.

5. In a wire netting machine, means to twist the wires, means to shift the wires laterally, a positioning device mounted upon a fixed support and engaging one side of each last-formed twist, and a second positioning device mounted upon a transversely movable support and engaging the opposite side of each such twist, said latter support being mounted to move with said twisting means but through a less range of movement.

6. In a wire netting machine, means to twist the wires, means to shift the wires laterally, and means to definitely position the last formed twists transversely relative to said twisting means and closely adjacent thereto.

7. In a wire netting machine, means to twist the wires, means to shift the wires laterally, and positioning means directly engaging the last-formed portion of the fabric to limit the lateral movement thereof, said positioning means being yieldable upwardly to permit passage of the diagonal mesh wires of the fabric.

8. In a wire netting machine, means to twist the wires, means to shift the wires laterally, a positioning device mounted on a fixed support at the rear of the fabric, a second positioning device mounted on a transversely movable support at the front of the fabric, and means to move said second support, said positioning devices being yieldable upwardly to permit passage of the diagonal mesh wires of the fabric.

9. In a wire netting machine, means to twist the wires, means to shift the wires laterally, a series of positioning devices mounted upon a fixed support and engaging the last-formed twists at the sides thereof, each of said devices having lateral lost motion on its support so that a twist which engages said device on either side thereof will be located thereby in the same transverse position in the machine.

In testimony whereof I have hereunto affixed my signature.

CHARLES W. HAWTHORNE.
